UNITED STATES PATENT OFFICE

2,551,063

SAFETY PIN

William H. Sneirson, Brookline, Mass.

Application November 10, 1948, Serial No. 59,299

2 Claims. (Cl. 24—156)

1

My present invention relates to safety pins and particularly to safety pins for use in the case of babies.

In taking care of babies, safety pins are widely used, with the most common example of their use being that of holding diapers in place. For that purpose, it is essential that a safety pin be adapted to hold securely, through several layers of cloth, against the pulls exerted by a healthy and lively baby and at the same time be capable of being easily opened and closed. While the standard safety pin has given acceptable service, wherever employed, it has not been entirely satisfactory for use in connection with the care of babies, in that it does not fully meet such requirements in that its accidental opening is an altogether too frequent occurrence.

In accordance with my invention, I provide a safety pin in which any possibility of its accidental opening is virtually eliminated. My pin has a plastic head in which one end of the back leg is embedded and which has a recess in its face that is disposed towards the connected ends of the legs. The recess is of such cross sectional shape as to establish a pocket spaced from the back leg in a plane normal to the legs, a channel, preferably sinuous, opening upwardly and outwardly through one side of the head to receive the pointed end of the front leg and located wholly on that side of the plane, and a second channel extending upwardly from that pocket and establishing a surface intersecting that plane and inclined upwardly towards the other side of the head. Preferably, the head includes a projecting ledge intermediate the channels to enable the user of the safety pin to tell at a glance which channel the pointed end of the front leg occupies.

The usual practice is to form both legs from suitable resilient stock with an intermediate coil yieldably maintaining the free ends of the legs normally spaced a predetermined distance apart. Where that practice is followed, I provide a guard for the coil which has the useful function, regardless of the head structure, of preventing cloth from becoming caught in the coil and lending to the attractive appearance of the safety pin. In practice, however, the guard has a slot through which the front leg freely extends and which defines a shoulder against which the front leg bears when pressed a predetermined distance towards the back leg so that further movement of the front leg towards its head entering position can be effected only by bending it.

By this construction, I am able to provide a

2

safety pin that is both attractive in appearance and combines maximum ease in opening and closing the safety pin and ensures against its being accidentally opened.

In the accompanying drawings, I have shown an illustrative embodiment of my invention from which these and other of its novel features and advantages will be readily apparent.

In the drawings:

10 Fig. 1 is a side view of a safety pin in accordance with my invention.

Fig. 2 is an edge view of the safety pin of Fig. 1.

Figs. 3 and 4 are sections, on an enlarged scale, along the lines 3—3 and 4—4 respectively of Fig. 1, and

Fig. 5 is a fragmentary view of the pin of Fig. 1 partly sectioned to show the ledge.

I have indicated at 10 and 11 front and back safety pin legs formed from resilient stock with an intermediate coil portion 12 yieldably maintaining the free ends of the legs normally a predetermined distance apart to establish the open position of the safety pin.

The free end of the leg 10 is embedded in a head 13 which is preferably molded from any suitable plastic, and to ensure that the leg 10 is securely anchored therein, its extremity is bent as at 14.

I form the head with a recess, generally indicated at 15, opening towards the coil portion 12 and of such cross sectional shape that it establishes a pocket 16 spaced from the embedded end of the leg 10 and in a plane, indicated at 17, normal to the legs, and a sinuous channel 18 extending upwardly and outwardly through one side of the head 13 and located wholly on that side of the plane 17 to establish an entrance for the pointed end of the leg 11 virtually abutting the embedded leg. In order that the entrance be as small as possible, its upper edge is shown in Fig. 1 as substantially parallel to the leg 10 while its lower edge is inclined downwardly towards the mouth of the recess to facilitate the entrance of the pointed end of the leg 11 therein.

Preferably, I provide the head 13 with a lip 19 adjacent that entrance so that, to close the safety pin, it is only necessary to press the leg 11 towards the leg 10 along the side of the head 13 until the lip 19 is passed. When the manual pressure on the leg 11 is released, the spring tension thereon forces it downwardly through that entrance and into the pocket 16. The recess 14 also includes a second channel 20 disposed to establish a surface 21 that intersects the plane 17 and is inclined upwardly relative

55

thereto towards the side of the head 13 opposite to the entrance for the leg 11 thereby preventing the opening of the safety pin unless the leg 11 is positively guided into and through the channel 18.

To facilitate the use of a safety pin in accordance with my invention, I form the head 13 with a ledge 22 which constitutes a part of the web 23 separating the channels 18 and 20. The ledge 22 enables the user to easily determine when the leg 11 has entered the channel 18 when the closed pin is to be opened.

I have shown my safety pin as having a guard, generally indicated at 24, enclosing its coil 12. The guard 24 consists of sections 25 and 26 as shown in Fig. 4 which enclose the coil portion 12 when assembled and one of them has a coil entering stud 27. The leg 10 extends through the periphery of the section 25 while the section 26 has a recess which establishes, in the assembled guard, a slot 28 through which the leg 11 freely extends when the safety pin is open. The slot 28 is dimensioned to provide a shoulder engageable by the leg 11 as it is moved a predetermined distance from its open towards its closed position so that the further movement of the leg 11 required to enable it to enter the head entrance results in the leg 11 being bent thereby increasing the locking pressure thereon.

From the foregoing, it will be apparent that safety pins, in accordance with my invention, are easily manufactured and are attractive in appearance. Not only do my safety pins minimize the chance of cloth being caught therein, but also are adapted to be easily opened and closed while being securely held in their closed position against accidental openings thereby making them well suited for use in the care of babies.

What I therefore claim and desire to secure by Letters Patent is:

1. A safety pin comprising front and back legs connected together at adjacent ends so that they

are maintained normally in a plane and so that their free ends are urged apart, and a rigid head adjacent to the back of which the free end of said back leg is rigidly connected, said head having therein adjacent to its front edge a pocket to accommodate the free end of the front leg when the pin is closed, said pocket lying in the normal plane of said legs, said head having therein a recess including two branches extending from said pocket toward the back edge of said head and defining therebetween a web, one of said branches being closed at its end nearer the back edge of said head and the other opening diagonally outwardly through one side of said head near the back edge of said head, the closed end of said first branch lying to one side of the normal plane of said legs, said second branch lying entirely to the other side of said plane, the free end portion of said web being disposed at the same side of said plane as the open branch of said recess and having its free edge spaced from the free end of the front leg when the latter is seated in said pocket.

2. A safety pin as set forth in claim 1 in which the inner end portion of the web extends as an indicator inwardly beyond the inner end of the head to facilitate removal of the free end of the front leg through the open branch of the recess.

WILLIAM H. SNEIRSON.
